UNITED STATES PATENT OFFICE.

EDWARD L. MEGILL, OF BROOKLYN, NEW YORK.

FEED-GAGE FOR PRINTING-PRESSES.

SPECIFICATION forming part of Letters Patent No. 712,198, dated October 28, 1902.

Application filed February 21, 1902. Serial No. 95,031. (No model.)

To all whom it may concern:

Be it known that I, EDWARD L. MEGILL, a citizen of the United States, residing in the borough of Brooklyn, county of Kings, and 5 city and State of New York, have invented certain new and useful Improvements in Feed-Gages for Printing-Presses, of which the following is a specification.

This invention relates to the class of feed guides and gages for the proper placing of the sheet on the platen of the press, of which class the gage described in the United States Patent No. 596,214, granted to me on December 28, 1897, is one example. The purpose 15 of the device is, in the main, to provide means for automatically placing properly a misplaced sheet through the medium of a gripper on the press. In my pending application, Serial No. 77,357, filed October 3, 1901, I show 20 and describe a feed-gage also belonging to this class and having some features like those in the gage device of this application. In a gage device of this class there is a base-plate secured on the platen, a sliding gage mounted 25 on said base-plate, a spring for retracting the sliding gage, and a hinged arm normally upheld by the spring in an inclined position and adapted to be impinged upon by the gripper when the platen moves up to the form, 30 thereby moving the head of the sliding gage up to the gage line or point on the platen. This is a feature common to automatic gages of this class and is embodied in the gage device of the present application. One of the 35 novel features of the present device is, however, an auxiliary means or device whereby the gripper is made to act more slowly and gradually on the sliding gage than in the device of my said patent.

40 Another feature of the present device is the construction whereby the sliding gage may be moved laterally about a center or pivotal point, so as to permit a heel on the gage-head to be inserted in a slit in the platen- sheet and an improvement in the retainer by 45 which the gage device is secured to the platen or platen-sheet.

In the accompanying drawings, which serve to illustrate my invention, Figure 1 is a plan 50 of the flattened gage device, showing in dotted lines the position of the gripper thereon. Fig. 2 is a plan of the gage device with the upper

portion broken away or removed. Fig. 3 is a transverse section substantially at line x^3 in Fig. 1. Fig. 4 is a front elevation of the gage device with the sliding gage and spring broken away. Fig. 5 is a perspective fragmentary view showing the rocking guide for the sliding gage. Fig. 6 is an under side view of the retaining-plate. Fig. 7 is a transverse section through one of the clamping devices of the gage. Fig. 8 is a front elevation of the gage device. Fig. 9 is a fragment of the end of the arched spring. Fig. 10 is a plan view of the gage detached. Fig. 11 is a general 65 view of a platen of a printing-press, showing the grippers and a gage device mounted on the platen.

In Fig. 11 X designates the platen of a printing-press, Y the grippers thereof, and 70 Z the tympan-sheet, stretched over the platen in the usual way and by the usual means. All of these parts are common in platen printing-presses and will require no special description.

75 S represents a sheet on the platen in position to be printed upon, the proper positioning of the sheet on the platen with respect to the form being secured ordinarily by a side gage or guide (usually at the left) and two front or bottom gages. In Fig. 11 the two front gages are designated as a whole by B B. They may be of any approved kind. The side guide or gage device which embodies the present invention is designated as 80 a whole by A. The specific construction of this gage device A will now be described with reference especially to Figs. 1 to 5. This class of devices, sometimes called "automatic sheet guides or setters," are made from 85 thin metal, so that when the gripper, which bears upon the device at the time the impression is made and flattens down the parts, will not be elevated appreciably. This device includes as old features a base-plate, 90 screw clamping devices to clamp said plate adjustably to a retainer which is to be secured to the platen or tympan-sheet, an operating-arm hinged to the base-plate and extending across the path of the gripper, a 95 broad arched resilient spring also hinged to the base-plate and situated under said arm so as to uphold it normally, and a gage mounted to slide in guideways on the base-

plate under said spring and movable transversely of the longitudinal axis of the gripper, said gage having an upwardly-curved gage-head and being coupled to the spring, so that when the latter is flattened it advances the gage and when it recovers its curvature by its resiliency it retracts the gage.

In the drawings, 1 is the base-plate, preferably made of sheet metal and of the contour seen in Fig. 2.

2 is the broad operating-arm, hinged in lugs 3 on the base-plate. Under and normally upholding the said arm is the broad arched spring 4, of thin spring metal, which is also hinged to the base-plate and independently of the plate 2. Under the spring and on the base-plate is pivotally mounted a rocking guide 5 for the sliding gage. This guide is pivoted at 5^a, Fig. 5, on the base-plate and is capable of swinging laterally about said pivot for reasons that will be hereinafter explained. In the guide 5 is mounted the sliding gage 6. (Seen detached and in plan in Fig. 10.) The body of the gage (which is made of thin sheet metal) slides in the guide 5, and it has a head 6^a, called the "gage-head," the extremity 6^b of which is T-shaped and curves upward, as best seen in Fig. 8. Being thin, springy, and resili- 30 ent, this gage-head may be flattened down by the gripper; but when the pressure is removed it will spring up again. As the T-head 6^b is normally quite elevated, when the sheet S is placed edgewise against it there is no danger of the sheet getting over the gage-head even though somewhat wrinkled. The purpose is to have the sheet take under the inner prong on the T-head, so that when the gripper flattens the gage down this prong (see Fig. 1) will extend in over the sheet S.

The broad arched resilient spring 4 operates the gage 6. This spring has in its front end, Fig. 9, a small aperture 4^a, which is engaged by a prong 6^c, Fig. 10, on the gage, so that when the spring is distended by flattening it advances the gage 6, and when it recovers its arched form (seen in Figs. 3 and 7) it retracts the gage. In order to prevent the sheet S from getting under the gage-head at the heel 6^d thereof, this heel is made to engage a slit z in the tympan-sheet, as seen in Fig. 1. When the gage-head moves in and out over the tympan, this heel plays in the slot, as shown in my former patent. Now the object of the rocking guide 5 is to permit the gage 6 to be turned laterally about the pivot 5^a to an extent sufficient to allow the heel 6^d to be inserted in the slot z after the gage device shall have been set in place on the platen. This does not impair the correct setting of the gage-head up to the gage line or point, as the broad spring 4 when flattened down is rigid laterally and holds the gage-head firmly and steadily in its proper position on the tympan-sheet.

The clamping devices, of which there are

two, consist each of a thin flat disk or plate 7, provided with an upright screw-stem 8 to receive a thin milled nut 9. The screw-stem 7^a passes upwardly through a hole in the base-plate.

The retainer 10 will be of metal or the like and of the form seen in Fig. 6. This retainer will be quite thin and have cross recesses or channels 10^a formed in its under side to receive the plates 7 of the clamping devices and elongated apertures 10^b for the passage of the screw-stems 8. The raised parts of the retainer formed by the bending of the plate to produce the cross-recesses project out to the front in order to furnish material in which to form the apertures 10^b, and in order to allow these extensions to be readily depressed slits 10^c are formed to 85 separate them from the adjacent end parts 10^d, which project out still farther. In applying the retainer to the platen or tympan-sheet paste or the like is applied to the surfaces of the parts 10^d and also to the surface 90 of the intermediate part 10^e. The base-plate may be clamped to the retainer 10 normally, and when the latter is secured to the tympan-sheet the base-plate can be adjusted on the retainer and then set fast thereon by the 95 clamping devices.

It is found that when the platen of a press closes up to the form and the gripper moves up to the platen the gripper does not impinge upon the arm 2 until the press is nearly 100 closed, and in consequence the movement of the sliding gage under the influence of the gripper is unduly rapid. To obviate this defect and cause the gripper to begin its operation sooner, so that it may depress the 105 spring 4 gradually, means are provided which will now be described with especial reference to Figs. 1, 3, and 11.

On the back or upper side of the arm 2, near its hinging-point, is mounted a bar 11, 110 provided near its end with an arm 12, which projects laterally from the bar and across the path of the gripper. This arm 12 performs a function similar to that of the arm 2, in that by the pressure of the gripper thereon the 115 arm 2 and spring 4 are depressed precisely as they would be if the gripper bore directly on the arm 2; but as in its operation the gripper impinges almost from the beginning of its movement on the arm 12 it will be obvious 120 that the movements of the gage 6 will be much slower than where the whole movement of the gage is confined to the terminal portion only of the movement of the gripper.

In order that the bar 11 may be readily removable from the arm 2 and that the arm 12 may be put into the path of the gripper at different distances from the gage, the bar 11 is mounted slidably in a guideway formed on the arm 2 by keepers 13 and 13^a, and a nick 13^b or recess 11^a is formed in the edge of the bar 11 of such length that when this recess is brought to register with the keeper 13 the bar 11 may be disengaged from the guideway.

The relative positions of the gripper and the gage device on the platen will vary somewhat with the conditions arising in printing. The position of the gripper in Fig. 1 is somewhat different, it will be noted, from that seen in Fig. 11. Where the operating-gripper does not take over the sheet, the prong on the gage-head which overlies the sheet will act as a stripper. In Fig. 1 the arm 2 and spring 4 are represented as pressed flat.

To impart a frictional resistance to the movement of bar 11 in its guideway, it may have a leaf-spring 14 under it, as indicated in dotted lines in Fig. 1. This is a common device to accomplish the object sought, and other known devices for the purpose may be employed as well.

It will be noted that the bar 11 extends longitudinally parallel with the surface of the platen and that the arm 12 thereon projects inwardly toward the middle of the platen, so that the gripper, which is designed ordinarily to take over the sheet to be printed, will always impinge upon it. The arm 12 is normally inclined to the surface of the platen and when impinged upon by the gripper the depression of the arm rocks the bar 11 and through it depresses the arm 2. One important advantage arising from this construction of the detachable bar 11 is the facility it affords for shifting the gage device to the right-hand side of the platen, as is sometimes required. In this case it is only necessary to remove the bar 11, turn it over, and place it again in the guideway on the arm 2.

Having thus described my invention, I claim—

1. An automatic registering-gage device having a slidable gage, a hinged arm and spring for operating said gage, and a bar connected with said hinged arm, and adapted to extend toward the lower edge of the platen, said bar being provided with a laterally-extending arm adapted to project toward the center of the platen and across the path of a gripper set to take over a sheet on the platen, and the head of said slidable gage being elastically compressible so that it may be pressed down flat by the said gripper, substantially as and for the purpose set forth.

2. An automatic registering-gage device having a slidable gage with a compressible spring-head, a spring for retracting said gage, an arm which is adapted to extend inwardly and laterally across the path of a gripper set to take over a sheet on the platen, and which is adjustable toward and from the gage, and mechanism between said arm and gage, whereby pressure of the gripper on said arm is communicated to the gage for operating the latter, and whereby the period during which the gripper acts thereon is prolonged, substantially as set forth.

3. In a gage device, the combination with a base-plate, a gage mounted slidably thereon, an arched, resilient spring connected to said gage for operating it, and an operating-

arm over said spring for flattening it, of a bar mounted on the said operating-arm and extending parallel with the base-plate and transversely of the path of the slidable gage, said bar being provided with an arm which extends laterally from the bar into the path of the gripper and is normally inclined with respect to the platen, and means for varying the distance between said arm and the gage, substantially as set forth.

4. In a gage device, the combination with a base-plate, a gage mounted slidably thereon, an operating-arm hinged to the base-plate, and means between the gage and said arm whereby depression of the latter actuates the gage, of the bar 11, mounted adjustably in keepers on the operating-arm and extending parallel with the platen and transversely of the path of the gage, said bar being provided with an inclined arm 12 which projects laterally and inwardly into the path of the gripper, substantially as and for the purposes set forth.

5. A gage device having a base-plate, a sliding gage mounted thereon, an arm 2 hinged to said base-plate, means between said arm and the gage whereby the depression and elevation of the arm actuates the gage, and a bar 11 mounted removably on said arm 2, whereby it may be removed and reversed, said bar being provided with an arm 12 which is normally inclined to the surface of the platen, substantially as set forth.

6. A gage device having a base-plate, a rocking guide 5 mounted pivotally thereon, and a sliding gage mounted therein, said gage having a gage-head provided with a heel to play in a slot in the tympan-sheet, substantially as and for the purpose set forth.

7. A gage device having a base-plate, a sliding gage mounted thereon and having a lateral motion at its head, said gage having a heel to engage a slit in the tympan, means for operating said gage, and means for holding it against lateral movement when advanced, substantially as set forth.

8. The combination with a gage device having clamping devices for securing it adjustably to a retainer, of a flexible sheet-metal retainer having cross-recesses in its under side formed by bending the sheet, the parts at said recesses being apertured to receive the clamping devices, substantially as set forth.

9. The combination with a gage device having clamping devices for securing it adjustably to a retainer, of a flexible sheet-metal retainer bent to form cross-recesses and elevated portions, said elevated portions having in them apertures to receive the clamping devices and projecting to form compressible extensions, substantially as set forth.

10. The combination with a gage device having clamping devices to secure it to a retainer, of the said retainer 10, made from a thin sheet of hard material with channels 10^a formed on its under side by bends in the material, said retainer having apertures 10^b at said chan-

nels to receive the clamping-screws, and slits 10° to separate the elevated portions from depressed end portions, substantially as set forth.

5 11. The combination with a gage device having clamping devices to secure it to a retainer, of the said retainer, formed from thin, flexible sheet metal having depressed portions to rest on the tympan and receive paste or the like for securing the retainer in place, and apertures in the parts not depressed to receive the screws of the clamping devices.

12. An automatic gage device having a sliding gage and a bar for operating same through 15 the gripper of the press, said bar having a lateral arm to receive the gripper, and being reversibly connected to the gage device whereby the latter may be operated from either side of the platen.

20 13. In a gage device for a platen printing-press, the combination with a base-plate, of a gage mounted thereon having a body and an elastic or spring-like head, said head being curved upward from said body to an extent 25 less than ninety degrees, so that it may be flattened down without folding on itself, and having a heel alined with it and adapted to traverse a slot in the tympan.

14. A gage device for a platen printing-press, comprising a base-plate, screw clamping devices for securing said base-plate in place, and a gage having its body slidably mounted on said base-plate, said gage having a spring-like head disposed at an angle to its body and curved upward at one end through 35 an angle of less than ninety degrees, the elevated extremity thereof having a lip or part which projects out laterally to take over the sheet in printing and the lower extremity thereof having a heel alined with it and adapted 40 to engage a slot in the tympan.

15. A gage for platen printing-presses having a body and an elastic or spring-like head provided with a branch which curves upward normally, said curved branch having at its 45 free end a part which projects laterally and rearwardly from said branch, whereby the gripper may take over it in depressing the said curved branch at its rear.

In witness whereof I have hereunto signed 50 my name, this 20th day of February, 1902, in the presence of two subscribing witnesses.

EDWARD L. MEGILL.
